PROCESS FOR A STABLE OIL SUSPENSION

Harold G. Garman, Kalamazoo, Mich., assignor to The Upjohn Company, Kalamazoo, Mich., a corporation of Michigan

No Drawing. Filed Jan. 3, 1957, Ser. No. 632,253

10 Claims. (Cl. 167—82)

This invention relates to a manufacturing process and more particularly to a process for preparing oil suspensions for pharmaceutical use.

The development of suspensions for pharmaceutical use frequently depends on the chemical and physical properties of the ingredients to be suspended. It is oftentimes desirable to prepare oil suspensions of various solid, oil-insoluble medicaments, especially where such medicaments are unstable in the usual aqueous vehicles.

A serious problem arises in the preparation of all pharmaceutical suspensions because of the lack of reliability of dosage. This unreliability of dosage results from the fact that many suspensions are not homogeneous when actually used because the suspended ingredients settle disproportionately and resuspend disproportionately or not at all. The inability to resuspend the ingredients of a suspension arises after the container has been stationary on the storage shelf for periods of time, has been transported in shipment or has been partially used by the ultimate consumer. These several difficulties have been severe enough in many cases that the settled material has been practically impossible to resuspend because of actual caking at the bottom of the container.

The principal object of this invention is to prepare stable oil-suspensions of solid, oil-insoluble medicaments that are suitable for pharmaceutical use. By stable suspensions are meant those in which the insoluble ingredients are suspended homogeneously throughout the vehicle for acceptable periods of time, and those in which the suspension can be reconstituted to its original homogeneous form with relative ease once the insoluble ingredients have settled to a degree after longer periods of time or after transportation to points remote from the locale of manufacturing. A further object of this invention is to prepare pharmaceutically elegant suspensions intended for oral use that are suitable for the variable dosage requirements of children and acceptable to all users as to appearance, smoothness and taste. Other objects will be apparent to those skilled in the art to which this invention pertains.

These and related objects have been accomplished by the provision of a process which comprises the intimate mixing and blending of the principal solid ingredients to be suspended in the oil vehicle by simultaneous reduction to a suitable particle size prior to suspending said ingredients in the oil vehicle. Separate reduction of particle size for each of the ingredients, even though carried out to the same specifications, does not produce a satisfactory suspension. The reason for this is not understood, but empirical results indicate that the process of this invention is generally applicable to oil suspensions of pharmaceuticals. This intimate blending and simultaneous reduction of particle size are preferably brought about by jet-pulverizing techniques, e.g., air-micronizing, but are not limited thereto since this step can be accomplished by other methods of comminution known in the art.

The term "air-micronizing" has reference to a method of reducing particle size by utilizing a jet of air under pressure in an enclosed chamber to bombard particles

2

against one another and the internal surfaces of the chamber. As examples of said other means the following may be cited: micropulverizing, milling, triturating, and micro-atomizing. Further examples of the many ways in which comminution can be carried out can be found in Chapter 11 of Remington's Practice of Pharmacy, Eleventh Edition, Mack Publishing Company, 1956.

Although the preferred use of the invention is in the preparation of suspensions for oral use, it is not limited thereto since the process of the invention is suitable also for the preparation of suspensions for parenteral use, especially where high concentrations of the insoluble ingredients are involved.

Oil suspensions of many medicaments can be prepared by the process of this invention. For oral use, the following can be prepared: antibiotics, oil-insoluble vitamins, ephedrine, anti-histaminic agents, theophylline, sulfonamide drugs, barbituric acid compounds, lipotropic agents, analgesics, ferrous sulfate, and the like. For parenteral use the following can be so prepared: adrenocorticotropic hormone, vasopressin, oxytocin, epinephrine, oil-insoluble vitamins, chlorionic gonadotropin, heparin, and the like. For oral use, various flavors and sweeteners may be incorporated into the suspension. Preservatives are also desirable. For oral use, it may be advisable to use certain adjuvants such as acacia, pectin, magnesium oxide, magnesium stearate, kaolin, aluminum hydroxide, salts of alginic acid or tragacanth. Preferred ingredients of the type referred to above are illustrated in the examples which follow.

The various solid ingredients to be suspended need not be in any special physical form prior to mixing and comminution, except with reference to mechanical limitations of the comminution technique used. Most ingredients are available in the trade in suitable physical forms, but occasionally an ingredient must be comminuted to a limited degree before being mixed with the other ingredients.

The comminution technique should be controlled to produce a suitable particle size of the ingredients to be suspended. Generally speaking, a suitable particle size is the same for mixed ingredients prepared in accord with the present invention as it is for individually processed ingredients. As a practical matter particle size can only be expressed as to range and distribution of particles within certain size limitations. These size limitations determine the particular specific surface for the ingredients to be suspended and thereby the rheological properties of the finished suspension. The suitability of a given suspension is a function of its rheological properties. However, as the present invention indicates, the suitability of an oil suspension of mixed ingredients for pharmaceutical use, is also a function of the manner in which the mixed ingredients are processed prior to suspension in the oil vehicle.

The acceptable range and distribution of particle size is 99 percent less than sixty microns and 75 percent less than twenty microns. However, with respect to the preferred embodiments of the invention as illustrated by the examples, it is preferred that the range and distribution of particle size be 99 percent less than from about 45 to about twenty microns and 75 percent less than from about twenty to about five microns.

Any fixed oil suitable for pharmaceutical use can be utilized as the vehicle for the suspension. Illustrative oils include vegetable oils (such as sesame, cottonseed, peanut, olive, corn, coconut, and the like), synthetic oils, and mineral oils. A gelling agent such as non-toxic salts of the fatty acids (such as aluminum monostearate) can also be used to help stabilize the suspension.

The basic formula of the products to which the present

process has been applied for the experimentation required for its perfection is as follows:

Principal ingredients:
 Adjuvant
 An active ingredient
 Cyclamate sodium
 Sweetener
 Secondary ingredients:
 A vegetable dye
 Flavors
 Vehicle:
 A vegetable oil
 A gelling agent for said oil

For the purpose of evaluating the effectiveness of this process in the preparation of oral suspensions, the procedure of shipping six to twelve containers of the various experimental suspensions by the usual means of truck and/or freight car shipments to points at least 1500 miles from the locale of manufacturing has been employed. Subsequently, said containers have been returned for examination and testing. Examples illustrative of the diversified experiments, procedures and results are set forth in the following tables.

TABLE I

Identification	Sucrose, percent	Adjuvant	Antibiotic	Cyclamate Sodium, percent	Oil	Gelling Agent
EM-435	30	Kelmar, 3%	K Penicillin G	2	Sesame	Aluminum Mono-stearate, 0.5%
ET-160	30	do	do	2	do	Do.
ET-162	30	do	do	2	do	Do.
ET-287	30	do	do	2	do	Do.

Kelmar is Kelco Company's brand of potassium alginate. After return from shipping destination, the contents of the above containers had caked badly and resuspension was practically impossible.

Powder processing details: Sucrose micropulverized. Cyclamate sodium and K penicillin G air-micronized separately. Kelmar not specially processed as to particle size.

TABLE II

Identification	Sucrose, percent	Adjuvant	Antibiotic	Cyclamate Sodium, percent	Oil	Gelling Agent
10,702-32	30	Kelmar, 3% Kaolin, 10%	K Penicillin G	2	Sesame	Aluminum Mono-stearate, 1%
10,702-33	30	do	do	2	do	Do.

After return from shipping destination, the contents of one container had caked slightly and in the other were too thick.

Powder processing details: Sucrose micropulverized. Cyclamate sodium and K penicillin G air-micronized separately. Kelmar not specially processed as to particle size.

TABLE III

Identification	Sucrose, percent	Adjuvant	Antibiotic	Cyclamate Sodium, percent	Oil	Gelling Agent
10,702-63	30	Kelmar, 1%	K Penicillin G	2	Sesame	Aluminum Mono-stearate, 1/2%
10,702-65	30	Kelmar, 2%	do	2	do	Do.
10,702-70	30	Kelmar, 1%	do	2	do	Aluminum Mono-stearate, 1.5%

After return from shipping destinations, the contents of the above containers had plugged and shaking did not remove the plug.

Powder processing details: Sucrose micropulverized. Cyclamate sodium and K penicillin G air-micronized separately. Kelmar not specially processed as to particle size.

TABLE IV

Identification	Sucrose, percent	Adjuvant	Antibiotic	Cyclamate Sodium, percent	Oil	Gelling Agent
10,702-80	30	Kelmar, 3%	K Penicillin G	2	Sesame	Aluminum Mono-stearate, 2%
10,702-81	30	do	do	2	do	Do.
10,702-82	25	do	do	2	do	Do.

After return from shipping destination, the contents of the above containers were too thick and considered unsatisfactory.

Powder processing details:
 80. Sucrose, cyclamate sodium and K penicillin G air-micronized separately. Kelmar not specially processed as to particle size.
 81. Sucrose and Kelmar air-micronized together. Cyclamate sodium and K penicillin G air-micronized separately.
 82. Sucrose and K penicillin G micropulverized together. Cyclamate sodium air-micronized. Kelmar not specially processed as to particle size.

TABLE V

Identification	Sucrose, percent	Adjuvant	Antibiotic	Cyclamate Sodium, percent	Oil	Gelling Agent
10,702-6	20	Kaolin, 10%	K Penicillin G	2	Cotton-seed.	Aluminum Mono-stearate, 1/2%.
10,702-7	20	do	do	2	do	None.
10,702	30	None	do	2	do	Aluminum Mono-stearate, 1/2%.
10,702-8	None	Kaolin, 30%	do	2	do	Do.
10,702-9	None	do	do	2	do	None.

After return from shipping destinations, the contents of the above containers had plugged or required shaking of the container after simple tilting, to resuspend.

Powder processing details: Sucrose micropulverized. Cyclamate sodium and K penicillin G air-micronized separately. Adjuvants not specially processed as to particle size.

TABLE VI

Identification	Sucrose, percent	Adjuvant	Antibiotic	Cyclamate Sodium, percent	Oil	Gelling Agent
10,702-28	20	Kaolin, 10%	K Penicillin G	2	Sesame	Aluminum Mono-stearate, 1/2%.
10,702-29	15	Kaolin, 15%	do	2	do	Do.
10,702-30	30	Kelmar, 3%	do	2	do	Aluminum Mono-stearate, 1.5%.

After return from shipping destinations, the contents of the above containers had caked to various degrees and were considered unsatisfactory.

Powder processing details: Sucrose micropulverized. Cyclamate sodium and K penicillin G air-micronized separately. Adjuvants not specially processed as to particle size.

TABLE VII

Identification	Sucrose, percent	Adjuvant	Antibiotic	Cyclamate Sodium, percent	Oil	Gelling Agent
10,702-47	30	Kelmar, 3%	K Penicillin G	2	Sesame	Aluminum Mono-stearate, 1/2%.
10,702-48	20	do	do	2	do	Do.

After return from shipping destinations, the contents of the above containers were too thick and/or had plugged to various degrees.

Powder processing details: Sucrose, cyclamate sodium and penicillin micronized separately. Kelmar not specially processed as to particle size.

TABLE VIII

Identification	Sucrose, percent	Adjuvant	Antibiotic	Cyclamate Sodium, percent	Oil	Gelling Agent
10,702-74	30	None	K Penicillin G	2	Sesame	Aluminum Mono-stearate, 1/2%.
10,702-75	30	do	do	2	do	Do.
10,702-76	30	do	do	2	do	Do.
10,702-77	30	do	do	2	do	Do.

After return from shipping destinations, the contents of the above containers had plugged and could not be resuspended.

Powder processing details: Penicillin milled or micropulverized. Cyclamate sodium air-micronized. Sucrose micropulverized.

TABLE IX

Identification	Sucrose, percent	Adjuvant	Antibiotic	Cyclamate Sodium, percent	Oil	Gelling Agent
10,702-57	30	Kelmar, 3%	K Penicillin G	2	Sesame	Aluminum Mono-stearate, 1/2%.
10,702-58	20	do	do	2	do	Do.

After return from shipping destinations, the contents of the above containers had plugged or were too thick. Powder processing details: Sucrose, cyclamate sodium and penicillin micronized separately. Kelmar not processed specially as to particle size.

Thus, Tables I through IX show various oil suspensions in which the ingredients were varied insofar as practicable as to type, concentration and particle size, but in no case did these variations result in a product which would withstand the shipping test. As clearly shown 75 suspensions capable of withstanding the shipping test.

by Table X, only intimate mixing by simultaneous combination of the principal ingredients to be suspended prior to suspension in the oil vehicle resulted in an oil

TABLE X

Identification	Sucrose, percent	Adjuvant	Antibiotic	Cyclamate Sodium, percent	Oil	Gelling Agent
11,097-1	25	Kelmar, 3%	K Penicillin G	2	Sesame	Aluminum Monostearate, 2%
11,097-3	25	do	do	2	do	Do.
11,097-5	25	do	do	2	do	Do.
11,097-6	25	do	do	2	do	Do.
11,097-7	20	do	do	2	do	Do.
11,097-8	20	do	do	2	do	Do.
11,097-14	22	Magnesium stearate, 3%	do	2	do	Do.
11,097-15	22	Magnesium stearate, 5%	do	2	do	Do.

After return from shipping destinations, the contents of each of the above containers could be resuspended by simple tilting of the container.

Powder processing details: All principal suspended ingredients mixed and then air-micronized together. Similar experiments with other medicinal ingredients, e.g., tetracycline and novobiocin produced similar results.

The following data on particle size are taken from production type lots of satisfactory oil suspensions of potassium penicillin G for oral use.

GA-154	GA-155	CA-237
99% less than twenty microns. 75% less than ten microns.	99% less than 25 microns. 75% less than twelve microns.	99% less than forty microns. 75% less than twenty microns.

The following data on particle size are taken from research type lots of satisfactory oil suspensions of potassium penicillin G for oral use.

11,097-1 and 2	11,096-5 and 6	11,097-7 and 8
99% less than forty microns. 75% less than fifteen microns.	99% less than thirty microns. 75% less than fifteen microns.	99% less than 45 microns. 75% less than fifteen microns.

The following examples are illustrative of the process of this invention and are not to be construed as limiting.

Example 1

The following process is the preferred embodiment in the case of an oil suspension of potassium penicillin G for oral use.

Each milliliter contains:

0.005% coloring material
0.3% Saccharin soluble powder U.S.P.
2% cyclamate sodium
25% cane sugar granular U.S.P.
3% Kelmar dried
(66,000 units) crystalline penicillin G potassium
0.2% flavors
Q.s. sesame oil-aluminum monostearate 2% gel

The coloring material is dissolved in the gel and the saccharin soluble added. The cyclamate sodium, sugar, Kelmar and penicillin are intimately mixed and blended by air-micronization and suspended in the oil vehicle. The flavors are added. The suspension is mixed thoroughly, processed through suitable dispersing equipment and strained through a 60 mesh stainless steel screen.

Particle size distribution of the air-micronized mixture:

99% less than forty microns
75% less than twenty microns

Example 2

The following process is the preferred embodiment in the case of an oil suspension of tetracycline for oral use.

Each milliliter contains:

0.007% coloring material
0.3% saccharin soluble powder U.S.P.

65

70

75

0.3% saccharin soluble powder U.S.P.
2% cyclamate sodium
25% sugar granulated U.S.P.
3% Kelmar dried
(55,000 units) potassium penicillin G
27.5 mg. calcium acid novobiocin
Q.s. sesame oil-aluminum monostearate 2% gel

The saccharin is added to the sesame oil-aluminum monostearate gel. The cyclamate sodium, sugar, Kelmar and penicillin are intimately mixed and air-micronized and added to the gel. The novobiocin acid calcium is added and the suspension is adjusted to volume with gel and processed through suitable dispersing equipment.

Particle size distribution of the air-micronized mixture:

99% less than twenty microns
75% less than ten microns

Example 4

The following process is the preferred embodiment in the case of an oil suspension of salicylamide for oral use.

Each milliliter contains:

0.3% saccharin soluble powder U.S.P.
20% salicylamide
2% cyclamate sodium
Q.s. cottonseed oil-aluminum monostearate 2% gel

The saccharin is added to the sesame oil-aluminum monostearate gel. The cyclamate sodium and salicylamide are mixed, air-micronized and added to the gel. The suspension is adjusted to volume and processed through suitable dispersing equipment.

Particle size distribution of the air-micronized mixture:
 99% less than thirty microns
 75% less than fifteen microns

The process of the invention can be utilized for the preparation of suspensions of other active ingredients and combinations of active ingredients, e.g., calcium acid novobiocin, penicillin and tetracycline, tetracycline and erythromycin, sulfa drugs, and sulfa drugs and novobiocin.

It is to be understood that the invention is not to be limited to the exact details of operation or compositions shown and described, as obvious modifications and equivalents will be apparent to one skilled in the art, and the invention is therefore to be limited only by the scope of the appended claims.

I claim:

1. In the process of preparing a stable oil suspension for pharmaceutical use, the step which comprises the intimate mixing and blending of at least one active principal solid ingredient and a plurality of other principal solid ingredients to be suspended in an oil vehicle by simultaneous reduction in suitable particle size prior to suspension in said oil vehicle, the particle size to be 99% less than 60 microns.

2. In the process of preparing a stable oil suspension for pharmaceutical use, the step which comprises the intimate mixing and blending of at least one active principal solid ingredient and a plurality of other principal solid ingredients to be suspended in an oil vehicle by 30

simultaneous reduction in particle size prior to suspension in said oil vehicle, the particle size distribution to fall within the range of 99 percent less than sixty microns and 75 percent less than twenty microns.

- 5   3. The process of claim 2 in which the particle size distribution falls within the range of 99 percent less than from about 45 to about twenty microns and 75 percent less than from about twenty to about five microns.
- 10   4. The process of claim 2 in which the principal solid ingredients include an oil-insoluble salt of penicillin.
- 5. The process of claim 2 in which the principal solid ingredients include an oil-insoluble salt of tetracycline.
- 6. The process of claim 2 in which the principal solid ingredients include an oil-insoluble salt of novobiocin.
- 15   7. The process of claim 2 in which the principal solid ingredients include salicylamide.
- 8. The process of claim 2 in which the principal solid ingredients include sucrose, potassium alginate, sodium cyclamate, and a therapeutically active ingredient.
- 9. The process of claim 2 in which the vehicle comprises a vegetable oil and a gelling agent.
- 10. The process of claim 2 in which the vehicle comprises sesame oil and aluminum monostearate.
